UNITED STATES PATENT OFFICE.

BARNEY S. BONAVENTURE, OF NEW YORK, N. Y.

ARCH SUPPORT.

Application filed March 13, 1925. Serial No. 15,297.

This invention relates to an arch support designed primarily for use in ballet slippers whereby it becomes possible for the wearer to dance on the toes with much greater comfort than has heretofore been possible, it enabling even an amateur to stand upon the toes with ease.

A further object is to provide a simple and efficient device of this character which can be placed readily upon the insole of a slipper and which is so constructed as to brace the foot at this point where subjected to the greatest strains.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings.

Fig. 1 is a side elevation of an arch support, a ballet slipper in which it is located being illustrated by broken lines.

Fig. 2 is a plan view of the device.

Fig. 3 is a section on line 3—3 Figure 2.

Fig. 4 is a section on line 4—4 Figure 2.

Referring to the figures by characters of reference, 1 designates a strip of sole leather shaped to correspond substantially with the insole of a ballet slipper S. The front or toe portion of this strip is slit transversely as shown at 2, said slit extending back close to the middle portion of strip 1 and also extending throughout the width of the strip.

Arranged longitudinally within the central portion of the slit 2 is a flat steel spring 3. This spring 3 is bowed in the direction of its length and is held to the bottom portion of the strip 1 by rivets 5. After the flat spring has been attached as described a cement, preferably a thin sheet of rubber, which has been indicated at 4 is placed between the thicknesses of the slit portion of the strip so that they will be caused to ad-

here and thus completely house the spring.

When the device is placed in a slipper the spring reinforced portion will bow upwardly as shown in Figure 1. Thus when the foot of the user is placed in the slipper the arched portion of the device will press against the foot back of the toes and toward the arch, thereby supporting the foot and reinforcing it at the point where subjected to the greatest strains while the user is standing on the toes.

What is claimed is:

1. As an article of manufacture a foot support for insertion in a ballet slipper to rest upon the insole, said support including a flexible strip having a transverse slit extending backwardly from its front end and terminating in the intermediate or arch portion of the strip, a bowed spring between the layers of the slit portion along the longitudinal center thereof and fixedly connected to one layer of the slit portion, and an adhesive for holding together the slit portion of the strip at the sides of the bowed spring.

2. An article of manufacture for use as a foot support for insertion into a ballet slipper, including a strip of flexible material adapted to be placed upon the inner surface of the insole of the slipper, said strip being slit transversely backwardly from its front end to a point adjacent the intermediate or arch portion, and a bow spring arranged longitudinally between the layers of the slit portion and extending from a point adjacent the front end thereof to the inner end of the slit at the arch portion, and means for holding the slit portion against opening after the spring strip has been inserted.

3. The combination with a ballet slipper of a foot supporting attachment formed of a flexible strip of material having its back portion resting upon the insole of the slipper and its front portion formed as an arch bridging the insole from the arch to the toe, and a resilient strip housed within that portion of the flexible strip bridging the insole.

In testimony that I claim the foregoing as my own, I have hereto affixed my signature.

BARNEY S. BONAVENTURE.
